UNITED STATES PATENT OFFICE.

JOHN E. RUNNELLS, OF WORCESTER, MASSACHUSETTS.

WATER-MEASURING MACHINE.

Application filed February 16, 1923. Serial No. 619,361.

To all whom it may concern:

Be it known that I, JOHN E. RUNNELLS, a citizen of the United States, residing at Worcester, in the county of Worcester and State of Massachusetts, have invented a new and useful Water-Measuring Machine, of which the following is a specification.

This invention relates to a machine for accurately measuring a continuous flow of water or other liquid during its passage through the machine.

My invention is particularly useful when applied to the measurement of boiler feed water which must be continuously supplied in relatively large quantities, and which is often heated to a comparatively high temperature.

It is the object of my invention to provide a machine for thus measuring water or other liquid which will operate continuously, which will automatically adjust its rate of operation to the flow of water, and which comprises few and simple parts which are easily assembled and which are reliable and efficient in operation.

My improved machine in its preferred form is of the duplex type in which the two parts or sections of the machine are filled and emptied alternately.

My invention further relates to arrangements and combinations of parts which will be hereinafter described and more particularly pointed out in the appended claims.

A preferred form of the invention is shown in the drawings, in which—

Fig. 1 is a side elevation partly in section, of my improved measuring machine;

Fig. 2 is a plan view thereof;

Fig. 3 is a detail plan view of the discharge part of one of the measuring tanks;

Fig. 4 is a detail plan view of the valve and port in the bottom of one of the discharge troughs, looking in the direction of the arrow 4 in Fig. 1;

Fig. 5 is an end elevation of the machine;

Fig. 6 is a transverse sectional elevation, taken along the line 6—6 in Fig. 2, and

Fig. 7 is a sectional side elevation similar to Fig. 1 but showing the parts in a different position.

Referring to the drawings, my improved measuring machine comprises a pair of rectangular measuring tanks 10 and 11 preferably formed as a single casing or chamber separated by a longitudinal center parti-

tion 12 (Fig. 6). Each tank 10 or 11 is provided with an overflow pipe 13 fixed in the bottom thereof and shown as increasing in diameter toward its upper end. A cap or cover plate 14 may be supported in spaced relation above the overflow pipe to prevent the entrance of foreign substances therein.

At its opposite end, each tank is provided with a plate having a sectional discharge port 15 (Figs. 1 and 3) which is normally covered by a hollow valve 16. This valve is preferably provided with a sleeve 17 at its center within which is received a rod 18 or plunger 18 having a bearing in the discharge port plate. Upward movement of the plunger in the sleeve is limited by a cross pin 19 and the upper end of the valve 16 is desirably closed by a cover plate 20.

The lower end of the plunger 18 is engaged by a block or plate 21 fixed to the inclined bottom 22 of one of the discharge troughs 23 and 24. The troughs 23 and 24 are rigidly secured together in reversed position and the united structure is pivotally supported by a knife edge 25 resting on bearing members 26 secured to the under side of the tanks 10 and 11.

At the lower end of each discharge trough there is provided a port 27 normally closed by a swinging gate valve 28. The valve 28 is connected by a chain or cord 29 to the bottom of the tank structure, the chain being of such length that the port 27 will be uncovered when the trough swings downward, as hereinafter described.

The opposite ends of the trough structure are connected by links 30 and 31 to oppositely disposed arms 32 and 33 on the ends of a rock shaft 34 mounted in open bearings 35 preferably supported on the center partition 12. A V-shaped deflector 36 is fixed to the rock shaft 34 and is adapted to be moved from the full line position to the dotted line position in Figs. 5 and 6 as the discharge troughs 23 and 24 rock upon the knife edge 25.

A supply pipe 37 is connected to a cross pipe 38 supported in a casing 39 above the deflector 36. The casing 39 may be mounted in any convenient manner but is shown herein as provided with pins 40 (Fig. 1) received in sleeves or tubes 41 fixed to the bottom of the tanks 10 and 11. The cross pipe 39 is provided with a narrow elongated slot 42 in its lower side through which a broad

flat stream of water may be discharged over the deflector 36 and into one of the tanks 10 or 11.

Having described the construction of my improved measuring machine the method of operation is as follows:—

Assuming the parts to be in the position shown in Figs. 1 and 6, the water will continue to flow into the tank 11 until the 10 water level reaches the top of the overflow pipe 13. Water will then flow down through the pipe 13 to the discharge trough 23 and will collect in the lower end of the trough above the gate valve 28. The trough 23 15 and 24 and all connected parts are carefully balanced so that only a small amount of water is necessary in the end of one of the troughs to reverse the position thereof, swinging the deflector 36 from the position 20 shown in full lines in Fig. 6 to the dotted lines shown in said figure. The parts at the moment of reversal are all shown in Fig. 7.

Rocking movement of the troughs is limited by stops 43 (Fig. 5) at both ends of the 25 machine and the permitted movement is not sufficient to overcome the incline of the bottom of the troughs, so that the ports 27 and valves 28 are always at the lower ends 30 of the troughs, whether in filling or discharge position.

As the right hand or deeper end of the trough 23 is depressed the valve 28 is relatively raised to open the port 27 and at the same time the associated valve 16 is raised 35 to open the port 15 in the bottom of the tank 11. Water will then flow through the discharge port 15 to the trough 23 and will escape therefrom through the open port 27.

In this way the trough 23 and tank 11 40 will both be entirely freed of water while the measuring tank 10 is being filled to the level of its discharge pipe. The parts will then be a second time reversed and this action will continue indefinitely, discharging a measured quantity of water at each reversal 45 of the machine.

A numbering device 45 (Fig. 5) may be connected by a link 46 to the rocking trough structure, thus recording the number of 50 reversals of the machine. By calibrating the machine to determine the exact amount of water or other liquid discharged by the machine at each reversal, the total quantity of water passing through the machine may be 55 easily determined after inspection of the numbering device 45.

The deflector 36 is made of sufficient weight so that it will slightly retard the reversal of the discharge troughs and will hold 60 them in one position until a sufficient amount of water collects in one of the troughs to overcome the unbalanced weight of the deflector.

The approximate amount of water 65 shown in the trough 23 in Fig. 7 represents

the weight necessary to overcome the deflector.

Having thus described my invention and the operation and advantages thereof, I do not wish to be limited to the details herein disclosed otherwise than as set forth in the claims but what I claim is:—

1. A water measuring machine having a pair of measuring tanks, a pair of discharge troughs, said troughs being pivotally mounted beneath said tanks and having their bottoms always inclined downward in opposite directions but at different angles in different operative positions of said troughs, means to deliver a relatively small quantity of water to its associated trough when one of said measuring tanks is filled to a predetermined point, and connections actuated by the weight of said overflow water effective to open discharge valves in said tank and trough and to deflect the flow of water to the second tank.

2. A water measuring machine comprising a pair of measuring tanks, each having an overflow pipe and a discharge valve, a discharge trough pivotally mounted beneath each tank and having an inclined bottom with a discharge valve at its lower end, a water supply, means to direct said water supply to either tank, and connections from said troughs to said valves and to said directing means, reversal of said troughs being occasioned by the accumulation of water from the overflow pipe of one of said tanks at the lower end of its associated trough and such reversal being effective to deflect the water supply to the second tank to open the discharge valves in the filled tank and its associated trough, and to close the discharge valves in the second tank and trough.

3. A water measuring machine comprising a pair of measuring tanks arranged side by side and each having an overflow pipe and a discharge valve at the opposite ends thereof, the overflow pipe in each tank being at the end of the tank adjacent the discharge valve in the other tank, a discharge trough pivotally mounted beneath each tank and having an inclined bottom with a discharge valve at its lower end, said bottoms being always inclined downwardly in a fixed direction but at different angles in different positions of said troughs, a water supply, a deflector to direct said water supply to either tank, and connections from said troughs to said valves and to said deflector, whereby reversal of said troughs by the accumulation of overflow water in one of said troughs is effective to open the discharge valves in the filled tank and its associated trough, to close the valves in the other tank and trough, and to deflect the water supply to the emptied tank.

4. A water measuring machine comprising a pair of measuring tanks, each having

an overflow pipe and a discharge valve, a discharge trough pivotally mounted beneath each tank and having an inclined bottom with a discharge valve at its lower end, a stop to limit rocking movement of said troughs to prevent reversal of the inclination of the bottoms thereof, means to direct a supply of water to either tank, valves controlling the accumulation of water in said tanks and troughs alternately in pairs, and means regulated by the rocking movement of said troughs and effective to reverse the water delivery to an empty tank and to open the valves in a filled tank and its associated trough, to discharge the water therein. In testimony whereof I have hereunto affixed my signature,

JOHN E. RUNNELLS.
